MANHOLE COVER AND MOUNTING MEANS THEREFOR

Eugene Porter Worthen, Braintree, and John Henry Stelling, South Yarmouth, Mass., assignors to Bethlehem Steel Corporation, a corporation of Delaware
Original application Aug. 22, 1960, Ser. No. 51,043, now Patent No. 3,254,705. Divided and this application Mar. 8, 1965, Ser. No. 437,749
2 Claims. (Cl. 220—25)

ABSTRACT OF THE DISCLOSURE

A manhole cover is mounted, inside a shell, through two pivotable links to a pin above the manhole opening, to permit the manhole cover to be swung to either side of the manhole opening. The links are above the manhole opening, thus permitting free access to the shell interior when the manhole cover is swung aside.

This application is a division of copending application Ser. No. 51,043, filed Aug. 22, 1960, now Patent No. 3,254,705, for Tubesheetless Butt welded U-Tube Type Combined Steam Generator and Non-Condensable Gas Extractor.

The present invention relates broadly to a manhole cover and means for mounting the same to the shell of a heat exchanger. More specifically, the present invention relates to a manhole cover and means for mounting the same to the inside of a steam generator so as to permit the same to be swung to either side of a manhole in the shell of the steam generator.

The present invention as described herein in connection with a tubesheetless, U-tube type steam generator employing a primary heating medium to boil a secondary fluid, such as water, to convert the same into steam and, in particular, with such a steam generator associated with a nuclear power plant, the primary heating medium being saturated steam from a nuclear reactor of the boiling water type. In a representative system, steam from such a reactor is introduced into the steam generator to raise steam in the secondary system. The secondary steam may then be used to operate a power plant. Of course, the steam generator described herein in connection with the present invention may use, as the primary heating medium, hot water or other hot fluid and may also use superheated steam.

As an example of the working conditions under which a steam generator of the type above described may operate, the said steam generator may receive primary saturated steam from a reactor at a pressure of 1000 p.s.i.a. (approximately 545° F.) to generate secondary saturated steam at a pressure of 600 p.s.i.a. (approximately 486° F.), the primary steam condensate leaving at about 545° F. and the secondary feed entering at about 486° F. These figures are given by way of illustration only.

Tremendous difficulties and high costs have been involved in the design and construction of conventional U-tube type steam generators used in conjunction with nuclear power plants. In addition to the high temperatures and pressures encountered, there is also the necessity of insuring that the primary steam, which may be contaminated by radioactive material, will not endanger personnel in the event of leakage in the equipment.

A steam generator of the type above described will ordinarily have a number of tubes therein which, from time to time, may require servicing of one sort or another. This in turn means that access through the shell of the steam generator to the interior thereof may be necessary from time to time, for instance to plug tubes or to withdraw tubes from the interior of the steam generator and to replace them.

2

An object of this invention is to provide a large manhole door or cover easily opened to either side of the manhole in the steam generator, giving quick and easy access to all the tube headers therein for inspection, repairing and plugging of tubes or for removal and installation thereof.

Other and further objects of the invention will become apparent during the course of the following description.

We have discovered that the foregoing objects can be attained by providing a particular configuration of manhole-cover supporting links hingedly mounting the manhole to the shell of the steam generator.

Referring now to the drawings, in which like numerals represent like parts in the several views:

FIGURE 1 represents a longitudinal section in elevation of a steam generator employing the present invention.

FIGURE 2 represents a longitudinal section in plan, taken along the line 2—2 of FIGURE 1, of a steam generator employing the present invention, showing in phantom the manhole cover swung to one side of the manhole.

FIGURE 3 is similar to FIGURE 2, showing in solid lines the manhole cover swung to the other side of the manhole opening, the position of said manhole cover intermediate such open position and the closed position being shown in phantom.

In the embodiment herein illustrated, the manhole cover and supporting means therefor constituting the present invention are seen as associated with a steam generator, the latter comprising drum or shell 1, with dished ends 2 and 3, containing six element header assemblies 4a—4f and a gas collecting header assembly 15. Header assemblies 4a—4f and 5 each, in turn, are seen to comprise four-element fittings 10 welded to stubs 11, the latter in turn being welded to the header assemblies 4a—4f and 5, U-tubes 12 welded to four-element fittings 10 and hand-hole plugs 13.

U-tubes 12 are spaced and supported in drum 1 by means of tube plates 33, the latter resting on a grid of beams 34 and 35 which are tied to the sides of the drum 1 and which are braced by box-like columns 36. Tube plates 53 are each associated with only one of the header assemblies 4a—4f and 5 to permit the withdrawal from said drum 1 of any one of said header assemblies 4a—4f and 5.

Access to the interior of drum 1 may be required for any of several reasons. For instance, when a U-tube 12 develops a defect, the openings in four-element fittings 10 corresponding to the defective U-tube may be plugged to permit continued operation of the steam generator until such time as it is convenient to replace the defective U-tube 12. When it is desired to replace the defective U-tube 12, the header assembly 4a—4f or 5 containing the defective U-tube 12 is removed from the interior of drum 1, the replacement operation is performed outside the drum 1, and the repaired header assembly 4a—4f or 5 is reinserted into the interior of drum 1.

Manhole 55 permits access to the interior of drum 1. Manhole cover 56 is located inside drum 1 and is provided with seat 57 which bears through suitable gasket means (not shown) against seat 58 of the manhole 55, the internal pressure in the operating steam generator serving to force said manhole cover 56 and seat 57 tightly against seat 58 through the aforesaid gasket means.

Bracket 59, mounted to drum 1 above the center of manhole 55, rotatably supports pin 60, the latter pivotally supporting link 61. Pin 62 pivotally connects links 61 and 63. Pin 64 pivotally connects link 63 and manhole cover 56 through brackets 65 secured to manhole cover 56 adjacent the center thereof. With this supporting arrangement, manhole cover 56 can be moved to either side of manhole 55, as shown in FIGURES 2 and 3, away from the side of drum 1 where space is required for working on equipment such as header handholes, etc. This feature permits a drum of shorter length to be used.

It is apparent that all of the header assemblies 4a-4f and 5 can be removed or installed one by one through the manhole 55. Welds 66 which join these assemblies to other piping in drum 1 such as conduits 15, 17, 20, and which join together the several parts of conduit 23, can be cut and rewelded easily to facilitate such removal or installation of the header assemblies 4a-4f and 5.

It will be seen that we have provided an easy-to-open manhole cover, which can be swung to either side of the manhole in the drum head, providing quick access to the headers for inspection, repair and plugging of tubes, and for removal of header assemblies.

The construction and operation of the specific steam generator herein briefly described insofar as considered necessary to a full understanding of the present invention forms, of course, no essential part of the present invention, and it is to be understood that the present invention is capable of use with apparatus of other types. A complete description of the construction and operation of the specific steam generator is found in the previously mentioned copending application Ser. No. 51,043.

We claim:

1. Manhole sealing means for use with a shell having a manhole opening and adapted to be swung to one side of said manhole opening or selectively to the other side thereof, comprising manhole cover means in said shell engageable with the periphery of said manhole opening to seal off said shell, a first vertically disposed pin mounted inside said shell above and clear of the manhole opening, a first link pivotally supported on said first pin clear of said manhole opening for swinging movement in a horizontal plane, a second vertically disposed pin mounted to the inner face of said manhole cover means, a second link pivotally supported on said second pin, said second link and said manhole cover means being rotatable relative to each other in a horizontal plane, and a third vertically disposed pin joining said first and second links for relative swinging movement in a horizontal plane.

5

2. Manhole sealing means for use with a shell having a manhole opening and adapted to be swung to one side of said manhole opening or selectively to the other side thereof, comprising:

- (a) manhole cover means engageable with the periphery of said manhole opening to seal off said shell,
- (b) a first pin mounted to said shell clear of said manhole opening with its longitudinal axis oriented towards the center of said manhole opening and intermediate the two extreme positions of said manhole cover,
- (c) a first link pivotally supported on said first pin clear of said manhole opening for swinging movement in a plane perpendicular to the longitudinal axis of said first pin,
- (d) a second pin mounted to said manhole cover means with its longitudinal axis parallel to the longitudinal axis of said first pin,
- (e) a second link pivotally supported on said second pin,
- (f) said second link and said manhole cover means being rotatable relative to each other in a plane perpendicular to the longitudinal axes of said first and second pins, and
- (g) a third pin with its longitudinal axis parallel to the longitudinal axes of said first and second pins joining said first and second links for relative swinging movement in a plane perpendicular to the longitudinal axes of said first, second and third pins.
